MACHINE FOR USE IN APPLYING PRESSURE
TO SHOE BOTTOMS

Elwin R. Everett, Conklin, N. Y., assignor to
United Shoe Machinery Corporation, Borough
of Flemington, N. J., a corporation of New
Jersey

Application April 10, 1939, Serial No. 267,020

13 Claims. (Cl. 12—33)

This invention relates to machines for use in applying pressure to shoe bottoms and is illustrated herein with reference to machines for cement attaching soles to shoes.

Machines of the type referred to are usually provided with a yieldable support such as a rubber pad for receiving a sole and shoe and with means such as abutments for engaging the shoe and the last therein and either pressing the sole and shoe forcibly into the surface of the pad, or positively supporting them against pressure applied by movement of the pad, for example, by inflation of the pad or bodily movement thereof toward the sole and shoe. In either case the sole and shoe are caused to sink or be depressed into the yieldable surface of the pad through relative movement of the latter and the shoe, the distance which the sole and shoe sink being variable and depending upon the operation being performed and the size of the shoe being operated upon.

Many machines for applying pressure to shoe bottoms, such as sole laying, sole leveling and cement sole attaching machines, are provided with mechanism for relatively positioning the sole and shoe on the pad before pressure is applied thereto. This mechanism usually comprises some sort of gages for engaging respectively the edge face of the sole and the opposite sides of the shoe and moving these members laterally relatively to each other until the proper positions are attained, there usually being further mechanism for actuating the gages and for maintaining them positively in operative engagement with the sole and shoe at least until sufficient pressure has been applied to prevent displacement thereof from their proper relative positions.

It will be seen that if gages or similar positioning means are maintained in operative engagement with the sole while the sole and shoe are being pressed against the yieldable surface of the pad to cause them to sink into such surface, or while the pad is being inflated which, in effect, produces substantially the same result, the sole and shoe will move heightwise relatively to the positioning gages and there is danger of the gages, especially the sole gages which may often be located in the path of movement of the shoe as it sinks into the pad, rubbing against the shoe and damaging the shoe upper by marks or scars.

An important object of the present invention is to provide improved positioning means in a machine of the type referred to whereby all

danger of damaging the shoe upper in this manner will be eliminated.

To this end I have provided, for use with a yieldable pad and means for causing a shoe and sole to sink into the supporting surface of the pad to apply pressure to the sole and shoe, improved means for positioning the sole on the pad constructed and arranged to bend while maintained in operative engagement with the sole and thus move or sink into the surface of the pad with the sole and shoe. As illustrated herein, the improved positioning means comprises a pair of sole gages arranged for equal and opposite lateral movement toward and from a sole on the pad, the gages being carried by flexible or resilient arms which permit the arms to bend under pressure and allow the gages to move in a heightwise direction with the sole and shoe when pressure is applied thereto. In this way the sole gages are prevented from engaging the shoe upper as it moves toward the pad and consequently cannot cause any damage thereto.

In accordance with a feature of the invention the gages are provided at their end portions with projections or extensions which project inwardly or toward each other and are arranged to underlie a sole placed on the pad so that, when pressure is applied to the sole and shoe, the extensions will become clamped between the sole and pad and thus lock the gages in operative position and cause them to move or sink into the yieldable surface of the pad with the sole and shoe. As illustrated, the extensions are composed of resilient material so that they can flex or bend heightwise as much as is necessary under the pressure applied to the shoe bottom.

With the above and other objects and features in view, the invention will now be described in connection with the accompanying drawing and will thereafter be pointed out in the claims.

In the drawing,

Fig. 1 is a plan view of the heel portion of a pad box embodying the present invention operating on a sole and shoe, the view being shown with portions of the mechanism removed or broken away;

Fig. 2 is a perspective view on an enlarged scale of one of the sole positioning gages;

Fig. 3 is a vertical section taken on the line III—III of Fig. 1, and

Fig. 4 is a sectional view similar to Fig. 3 but with the sole and shoe under pressure.

The invention is illustrated herein by way of example with reference to a machine for cement attaching soles to shoes such as that disclosed in

Letters Patent of the United States No. 2,047,185, granted July 14, 1936, in the name of Milton H. Ballard et al., and more particularly the invention is disclosed as embodied in a pad box of the type shown in Letters Patent of the United States No. 2,005,755 granted June 25, 1935, in the name of Francis J. Better. It is to be understood, however, that the invention is not intended to be limited in its application or use to cement sole attaching machines or pad boxes of the types disclosed in the patents mentioned since, in its more general aspects, the invention is well adapted for use with practically all types of machines for applying pressure to shoe bottoms in which the sole and shoe are engaged by a yieldable support or pad and are pressed or sunk into the surface of the pad by relative movement of the pad and shoe.

As disclosed in the Better patent referred to, the pad box comprises a frame 10 in which is mounted a flexible pad 12 the rear portion of which is retained in the frame by overlapping plates 14 and 16, the pad 12 being in the form of a closed chamber or bag composed of elastic material such as rubber and being filled with fluid such as water.

The heel end of the frame 10 (Fig. 1) is provided at its opposite sides with vertical guideways (not shown) in which is mounted a slide carrying a rearwardly extending bracket 18, the slide and bracket being arranged for vertical adjustment in the guideways as well as for downward yielding movement against compression springs (not shown) which normally maintain the slide and bracket in their uppermost positions. At its upper end the bracket 18 supports a group of horizontal castings or plates 20 two of which are provided with T-slots 22 extending transversely of the pad box, only the lower plate being shown in Fig. 1 of the drawing. In each of the transverse slots 22 is mounted a slide 24 arranged for movement widthwise of the pad and provided with an inclined cam slot 26 which is engaged by a projection or pin 28 carried by each of two pairs of gages, a lower pair 30 for positioning the heel portion of a sole A on the pad 12, and an upper pair 32 for engaging the opposite sides of a shoe S on the sole and positioning the shoe relatively to the sole.

As shown in the Better patent, both pairs of positioning gages are pivotally mounted on pins 34 carried by further plates (not shown) located between the slotted plates 20. The gages of each set are interconnected for equal and opposite swinging movement about their respective pivots by intermeshing gear segments 36 formed on the rear portions of the gages. The operation of both sets of gages to move them toward and from the sole and shoe is effected by movement of the transverse slides 24 whereby, through the inclined cam slots 26 and projections 28 referred to, the gages of each set are swung about their pivots equal amounts in opposite directions. As is also disclosed in the Better patent, the slide 24 for the lower or sole gages 30 is caused to move forwardly or toward the right, as viewed in Fig. 1, into the position shown in that figure by treadle operated mechanism (not shown) including a bell crank lever which is arranged to engage the left-hand end of the slide 24 and move it forwardly in the slot 22 against the action of a compression spring which normally holds the slide in its rearward or inoperative position.

The shoe gages 32 are moved inwardly into

engagement with the shoe, which is the position shown in Fig. 1, by forward movement of their actuating slide through the manual operation of a swinging frame member (not shown) on the cement sole attaching machine when such member is swung by the operator into operative position over the sole and shoe on the pad box, this swinging member carrying last and shoe engaging abutments which are operated thereafter to press the sole and shoe forcibly against the pad and apply the sole attaching pressure. A fragment of the last engaging abutment on the swinging frame is indicated in Figs. 1, 3 and 4 by the numeral 38. Both sets of positioning gages are positively retained or locked against movement away from the sole and shoe after they have positioned them on the pad by reason of the angles of inclination of the cam slots 26 in the transverse slides 24, these angles being such that the friction between the parts prevents movement of the slides in a direction to retract the gages. As shown in Figs. 1 and 3, the shoe gages 32 are provided with end portions 40 which are elongated heightwise of the shoe and are arranged to be retained in vertical slots 42 in the gage arms by compression springs 44 whereby the elongated members 40 may be quickly reversed in the slots to adapt them for operating on both large and small shoes.

The sole gages 30 comprise forwardly extending arms or fingers 46 rigidly secured to the interconnected segmental portions 36 of the gage members, the arms 46 being of substantial width but extremely thin heightwise and composed of flexible or resilient material, such as spring steel, which will bend readily without breaking under pressure exerted in a direction extending heightwise of the pad. The arms 46 are wide enough so that they cannot bend or flex laterally and, accordingly, they will operate positively to engage and position the sole widthwise relatively to the pad and shoe when actuated as explained above. As herein illustrated, the flexible arms 46 are secured by rivets 48 in horizontal slots formed in the segmental portions 36 of the gages, although they could obviously be secured to these portions in other ways or could be formed integrally therewith, if desired.

At their forward ends the flexible arms or fingers 46 have secured to their lower sides by rivets or similar means 50 (Fig. 2) sole engaging members 52 which constitute the sole gages proper, these gages being much thicker than the arms 46 but, as shown in Figs. 3 and 4, being somewhat thinner than an outsole for small shoes, such as children's shoes. At their inner or work engaging ends the sole gages 52 have forwardly projecting ribs or lips 54 which are provided for actually contacting with the edge face of the outsole at some point between its inner and outer surfaces and over a relatively thin section heightwise thereof, this construction being utilized to help prevent foreign matter such as scraps of leather and so forth getting between the sole gages and causing them to position the sole inaccurately with respect to the shoe bottom. On their bottom surfaces the sole gages 52 are provided with inwardly extending projections 56 which, as herein illustrated, comprise thin resilient plates composed of material such as spring steel, which will bend or flex readily under pressure exerted heightwise of the pad. The spring plates or extensions 56 may be secured to the bottom surfaces of the gages 52 in any suitable manner for example, as herein shown, by the

rivets 50 which also secure the gages to the arms or fingers 46. The resilient plates 56 project inwardly beyond the ends of the gages 52 about an inch or an inch and a quarter and, to insure 5 against their becoming loose on the gages 52 or springing away from the inner portions thereof, they are also secured to these inner portions by another screw or rivet 58 (Fig. 2) positioned adjacent to the sole engaging ends of the gages.

10 It will be seen from the foregoing description that the sole positioning gages 30 at each side of the pad can be moved positively toward and away from a sole because the gage arms 46 cannot bend laterally due to their width. When the 15 gages move inwardly to engage the opposite edge faces of the sole, only the lips 54 contact therewith so that the gage members actually engage the edge faces of the sole at relatively thin sections heightwise thereof. The resilient projections or plate 56, however, are always resting on the pad in a position in which they will partially underlie any sole placed thereon regardless of the size of the sole and even though the gages 20 52 are in their outer or retracted position. Accordingly, the operator places the sole A on the pad with the heel portion thereof overlying the 25 projections or plates 56. He then actuates the sole gages in the manner described above to cause them to move at equal speeds toward the opposite 30 edges of the sole, the plates 56, of course, sliding inwardly on the pad farther under the sole which is then resting lightly on the pad without a shoe thereon. The lips 54 of the gages 52 engage the sole and, if necessary, move the sole laterally 35 of the pad into a properly centralized position determined by the sole gages.

The shoe S is then placed on the sole A, the opposing surfaces of the sole and shoe in the case of the cement attachment of these members 40 to each other, having been first treated with cement preparatory to the sole attaching operation. The operator then moves the shoe gages 32, 40 inwardly at equal speeds, as described above, until the end portions 40 thereof engage the opposite 45 sides of the heel portion of the shoe at the widest part thereof, as shown in Fig. 3. Since both sets of gages are prevented from moving away from the sole and shoe by reason of the inclined cam slots and projections referred to, the heel portions 50 of the sole and shoe will thus become properly located relatively to each other and will be held in such position on the pad. The pressure applying abutments, including the heel abutment 38, are next operated to apply the sole attaching pressure by pressing the sole and shoe 55 forcibly against the yieldable surface of the flexible pad 12. The pad will yield under such pressure, thereby permitting the sole and shoe to sink a certain distance into its supporting surface 60 as shown in Fig. 4, the distance which the sole and shoe sink into this surface being controlled by the amount of pressure applied and the size of the sole and shoe being operated upon.

As the sole and shoe sink into the pad the resilient plates or projections 56 become clamped 65 between the sole and pad and thus lock the sole gages positively in operative position so that the gages 52 are caused to move downwardly or sink into the yieldable surface of the pad with the sole 70 and shoe. During this movement the gages 52 remain in operative relation with the sole with the thin lips 54 engaging its opposite edge faces, as shown in Fig. 4. The flexible nature of the projections 56 permits them to bend as much as is 75 necessary in a heightwise direction under the

pressure of the sole and shoe against the pad. In like manner, the resilient arms 46 will bend as much as is required heightwise of the shoe (as shown in Fig. 4) to allow the gages 52 to sink with the sole and shoe into the surface of the 5 pad. There may also be a small amount of torsional action required of the gage arms 46 about axes extending lengthwise of the arms when the gages 52 are deflected out of a substantially horizontal position as they sink into the pad but this torsional action will never be so great but the arms can readily accommodate it to permit the gages 52 to sink into the pad while remaining in operative engagement with the sole.

The gages of the present invention, therefore, 10 provide means for positioning an outsole on a yieldable pad relatively to the bottom of a shoe which is to be pressed against the sole and pad, which means does not have to be retracted from engagement with the sole to prevent damaging 15 the shoe upper by rubbing against it and producing marks or scars thereon during relative movement of the shoe and pad, whether the pressure is applied by forcing the sole and shoe into the yieldable surface of the pad or whether, as in 20 some cases, the pressure is applied by positively engaging the shoe by abutments and preventing its movement relatively to the pad while the surface of the pad is distorted by inflation or otherwise to apply pressure and cause said surface to 25 wrap itself around the sole and shoe bottom and to bulge outwardly at portions thereof which lie outside the periphery of the sole. It will be seen, moreover, that the sole engaging lips 54 of the 30 gages 52 facilitate the action of the gages in sinking into the pad with the sole and shoe because they engage only a thin section heightwise of the sole and, consequently, permit the gages 52 readily to assume different angular positions relative 35 to the plane of the sole as the gages sink into 40 the pad.

Having thus described my invention, what I claim as new and desire to secure by Letters Patent of the United States is:

1. A machine for applying pressure to shoe bottoms having, in combination, a pad provided with a yieldable surface for receiving a sole and shoe, means for effecting relative movement of said surface and the sole and shoe to cause the sole and shoe to sink into said surface, and means for 45 positioning the sole on said surface before the shoe is mounted on the sole, said means being constructed and arranged to bend and move into said yieldable surface with the sole and shoe when they are pressed into said surface. 50

2. A machine for applying pressure to shoe bottoms having, in combination, a pad provided with a yieldable surface for receiving a sole and shoe, means for effecting relative movement of the sole and shoe and said yieldable surface to cause 55 the sole and shoe to be depressed into said surface, and resilient means for positioning the sole on said surface constructed and arranged to engage the edge face of the sole and to bend and move into said surface with the sole and shoe 60 when they are depressed into said surface.

3. A machine for applying pressure to shoe bottoms having, in combination, a yieldable pad for receiving a sole and shoe, means for applying pressure to the sole and shoe to cause them to 65 sink into said pad, and flexible means arranged to engage the opposite edge faces of the sole and to position the sole on the pad, said means being constructed and arranged to become 70 clamped between the sole and pad when pressure 75

- is applied to the sole and shoe and to sink into the pad with the sole and shoe during the pressure applying operation.
4. A machine for applying pressure to shoe bottoms having, in combination, a pad provided with a yieldable surface for receiving a sole and shoe, means for effecting relative movement of said surface and the sole and shoe to cause the sole and shoe to sink into said surface and thereby have pressure applied thereto, and means for relatively positioning the sole and shoe on the pad before pressure is applied, the sole positioning means being arranged to bend heightwise and sink into the surface of the pad with the sole and shoe.
5. A machine for applying pressure to shoe bottoms having, in combination, a pad provided with a yieldable surface for supporting a sole and shoe, mechanism for applying pressure to the sole and shoe to cause them to sink into said surface, and means for relatively positioning the sole and shoe before pressure is applied thereto, said means including a pair of resilient members arranged to engage the opposite sides of the sole and to bend heightwise while in operative engagement with said sole as the sole sinks into said yieldable surface, thereby permitting said resilient members to sink into said surface with the sole and shoe to avoid damaging the shoe upper.
- 20 6. A machine for applying pressure to shoe bottoms having, in combination, a pad provided with a yieldable surface for receiving a sole and shoe, mechanism for applying pressure to the sole and shoe to cause them to sink into the yieldable surface of the pad, and means for positioning the sole relatively to the shoe, said means comprising resilient members arranged to engage the opposite edge faces of the sole and to bend heightwise of the pad under pressure exerted
- 30 7. A machine for applying pressure to shoe bottoms having, in combination, a pad provided with a yieldable surface for receiving a sole and shoe, mechanism for applying pressure to the sole and shoe to cause them to sink into said yieldable surface, and means for relatively positioning the heel portions of the sole and shoe before pressure is applied thereto, said means including resilient members for engaging the sole and arranged to bend heightwise of the sole while in operative engagement therewith, thereby permitting said members to sink into the surface of the pad with the sole and shoe when pressure is applied thereto.
- 50 8. A machine for applying pressure to shoe bottoms having, in combination, a pad provided with a yieldable surface for receiving a sole and shoe, mechanism for applying pressure to the sole and shoe to cause them to sink into the surface of the pad, means for positioning the heel portion of the sole relatively to the pad, said means comprising a pair of flexible arms arranged to bend heightwise of the pad under pressure applied in that direction and having sole
- 60 9. A machine for applying pressure to shoe bottoms having, in combination, a pad provided with a yieldable surface for supporting a sole and shoe, mechanism for applying pressure to the sole and shoe to cause them to sink into the surface of the pad, and means for positioning the sole relatively to the pad, said means comprising a pair of resilient arms arranged for heightwise and torsional flexing action under pressure and having sole engaging portions thereon adapted to engage the opposite edge faces of the sole, said arms permitting said sole engaging portions to remain in operative engagement with the sole during pressure and to sink into the surface of the pad with the sole and shoe.
10. A machine for applying pressure to shoe bottoms having, in combination, a yieldable pad provided with a surface for supporting a sole and shoe, mechanism for applying pressure to the sole and shoe to cause them to sink into the surface of the pad, and means for positioning the sole relatively to the pad, said means comprising a pair of flexible arms provided with sole engaging portions for engaging the opposite edge faces of the sole and arranged for heightwise and torsional flexing movement under pressure, and projections on said portions arranged to extend between the sole and pad and to become clamped in such position when the sole and shoe are pressed against the pad, thereby locking said arms in operative engagement with the sole so that they will be caused to flex heightwise and torsionally under pressure and sink into the surface of the pad with the sole and shoe.
11. A machine for applying pressure to shoe bottoms having, in combination, a pad provided with a yieldable surface for receiving a sole and shoe, a pad box for supporting said pad, mechanism for applying pressure to the sole and shoe to cause them to sink into the surface of the pad, means carried by the pad box for engaging the sole and positioning it relatively to the pad before the shoe is mounted thereon, said means being constructed and arranged to bend when pressure is applied thereto, extensions on said pad and to be clamped therebetween when the sole and shoe are pressed against the pad, thereby causing said positioning means to bend and sink with the sole and shoe into the surface of the pad, and means for actuating said positioning means.
12. In a machine for cement attaching soles to shoes, gages for positioning a sole relatively to a shoe before the sole is attached to the shoe bottom, said gages comprising resilient arms movable laterally toward and from the sole and arranged to locate it in a predetermined position relatively to the shoe, said arms being arranged to bend heightwise of the sole under pressure to permit them to move in a heightwise direction with the sole, sole engaging members carried by said arms for engaging the opposite edge faces of the sole, and projections on said sole engaging members arranged to underlie the sole and to cause the sole engaging members to move heightwise with the sole when the sole is pressed against said projections.
13. In a machine for cement attaching soles to shoes, a plurality of gages for relatively positioning a sole and shoe before they are attached to each other, said gages including resilient mem-

bers for positioning the sole relatively to the shoe bottom, said resilient members comprising arms movable positively toward and away from the sole and provided at their outer ends with sole engaging portions adapted to engage the opposite edge faces of the sole between the inner and outer surfaces of the sole, and resilient extensions on said sole engaging portions arranged to underlie

the sole, said arms being constructed and arranged upon movement of the sole against said extensions to bend heightwise and thus permit said sole engaging portions and extensions to move with the sole while in operative engagement ⁵ therewith.

ELWIN R. EVERETT.
